UNITED STATES PATENT OFFICE.

HAL R. STAFFORD, OF NORTH PLAINFIELD, NEW JERSEY; MARY M. STAFFORD
ADMINISTRATRIX OF SAID HAL R. STAFFORD, DECEASED.

INVISIBLE CAB-TURRET.

1,392,457.

Specification of Letters Patent.

Patented Oct. 4, 1921.

Application filed November 17, 1919. Serial No. 338,634.

To all whom it may concern:

Be it known that I, HAL R. STAFFORD, a citizen of the United States, residing at North Plainfield, in the county of Somerset 5 and State of New Jersey, have invented certain new and useful Improvements in Invisible Cab-Turrets, of which the following is a specification.

The first of the objects of this invention 10 is the provision of a device of the character specified which will provide a supply of dry steam for the purpose of operating locomotive auxiliary devices without obstructing the locomotive cab as is done with the ordinary arrangement of cab turret.

A further object of the invention is the provision of a convenient arrangement of apparatus whereby the auxiliary valves may be placed upon the outside shell of the boiler 20 and operated from within the cab while at the same time removing all the piping from the locomotive cab.

A further object of the invention is the provision of one or more manifolds placed 25 within the boiler shell supplied by dry pipes from the dome and constructed with a reinforcing plate riveted to the outside of the shell to compensate for the weakening of the shell that would be otherwise caused by the 30 tap holes provided for the valve connection.

A further object of this invention is the provision of a device which will insure a much better location of the steam supply 35 valves attached to the turret and which will afford much greater safety to the engine crew and protection against danger of scalding on account of the knocking off of the turret or parts and the escapement of steam 40 in case of accident.

Still another object of this invention is the provision of an arrangement which can be most advantageously used in export locomotives inasmuch as it will be unnecessary 45 with this device to remove the cab turret in shipping the boilers without cover. The apparatus also can be made more cheaply than those heretofore employed and will be more serviceable in use.

50 The above as well as such other objects as may hereinafter appear, I obtain by means of a construction which I have illustrated in preferred form in the accompanying drawings, wherein—

55 Figure 1 is a side view of a portion of an

engine cab having part of the wall and roof broken away and a portion of the turret mechanism shown in section to more readily disclose the features of my invention.

Fig. 2 is a transverse sectional view on the line 2—2 of Fig. 1; Fig. 3 is a plan view of the device shown in Figs. 1 and 2; Fig. 4 is a plan view of a modified arrangement employing but a single turret in place of the pair of turrets shown in Fig. 3. Fig. 5 is a diagrammatic plan view of an arrangement employing a pair of turrets located in front of the forward wall of the cab with operating rods extending laterally and backward and connecting with actuating handles located within the cab whereby all of the piping may be arranged upon the outside of the cab and yet ready access obtained through the operating valves by handles accessible to the engineer or fireman within the cab. Fig. 6 is a side elevation of the turret casing itself and Fig. 7 an end view of the same.

Referring now more particularly to Fig. 1, it will be seen that I have therein shown a cab 1 having a roof 2 broken away in order to expose to view the interior within which I have indicated in sectional view, the introduction of the interior turret casing 3 secured to the top sheet of the boiler as shown by means of a plurality of rivets 4 extending through flanges 5 there being a forwardly extending nozzle or projection 6 which is connected at 7 with a dry pipe coming back from the steam dome of the locomotive or other convenient source of supply.

As will be clear from examination of Figs. 1 and 2, the turret casing 3 is located upon the interior of the boiler shell with certain of the adjacent crown sheet rods or bolts 8 passing through the flange to aid in securing the parts in place, and there is provided upon the outside of the boiler shell a plate 9 which reinforces the shell and provides compensating strength as against the weakening effects of the apertures formed in the shell by the connection of the supply pipes thereto. Various outlets from the turret are shown including a large one marked 10 which may be for supplying the injector and a number of small ones 11 which may be used for other purposes common on locomotives.

As shown in Figs. 6 and 7, the turret casing 3 is formed of sheet metal bent into the shape indicated and preferably welded.

along the line marked 12 in Fig. 7 which, being upon the inner bend or curve, will not be subject to the same tendency to breakage or opening at the seam as would be a joint along the opposite side. It is to be observed that the pressure on this device is fundamentally greatest upon the outside wherefore there should be no difficulty with the welded form shown. This condition also obtains with regard to the position of the flange 5 with relation to the boiler shell so that it is not essential to use a very large number of rivets to insure a tight joint in fastening the shell to the turret casing, and the provision of the outside plate 9 is more for stiffening the metal of the shell and strengthening the device to compensate for the weakening effect of the pipe connections than from need of obtaining a tight steam joint.

Referring particularly to Fig. 5, it will be seen that I have therein indicated a pair of inside turrets located forward of the front wall 13 of the cab and having the valves connected by universal joints indicated at 14 at opposite ends of the rods 15 and arranged to be actuated by the handles 16 within the cab. By this arrangement all the piping and connections may be disposed outside the cab and still have the valve devices actuated from handles convenient of access upon the interior of the cab as will be readily apparent.

I claim:

- 35 1. A locomotive boiler having a steam turret secured upon the inside of the boiler and steam supply valves connected with said turret, but located upon the outside of the boiler.
- 40 2. A turret for steam boilers having a flange for attachment upon the inside of a boiler shell, a dry pipe connection to said turret, an outlet from the turret with a

valve for controlling said outlet located upon the outside of the boiler shell. 45

3. A turret located upon the inside of the boiler shell, a supply valve upon the outside of the boiler shell communicating with said turret, and a strengthening plate upon the outside of said boiler shell with means for 50 securing the plate and turret together.

4. A turret located upon the inside of the boiler shell, a supply valve upon the outside of the boiler shell communicating with said turret, and a strengthening plate upon the outside of said boiler shell with means for 55 securing the plate and turret together, said means comprising a plurality of rivets passing through the flange of the turret and the plate. 60

5. A turret located upon the inside of the boiler shell, a supply valve upon the outside of the boiler shell communicating with said turret, and a strengthening plate upon the outside of said boiler shell with means for 65 securing the plate and turret together, said means comprising a plurality of rivets, and a plurality of stay bars.

6. A turret located upon the inside of the boiler shell, a supply valve upon the outside 70 of the boiler shell communicating with said turret, and a strengthening plate upon the outside of said boiler shell with means for securing the plate and turret together, said means comprising a plurality of rivets, and 75 a plurality of stay bars, the turret being located between adjacent rows of said stay bars.

7. In a boiler, the combination of a steam turret located therein, a steam supply pipe 80 from the turret extending through the boiler shell, and means for controlling the supply through said pipe.

In testimony whereof, I have hereunto signed my name.

HAL R. STAFFORD.
